ABSTRACT OF THE DISCLOSURE

The disclosure herein relates to apparatus and a process for blending multifiber slivers wherein slivers of fiber are conducted from the creels in a drawing frame into the back rolls of a drafting head by guide mechanisms which flatten each of the separate slivers and assemble the flattened slivers into superimposed relation so as to form a web before the slivers reach the back rolls.

The present invention relates to improved apparatus and a process for producing blended yarns of two or more fibers of varying characteristics and, more particularly, to improved apparatus and processes for producing a flattened sheet configuration which can be combined with other similar blended sheets and subjected to other apparatus to provide uniformly blended yarns and the like.

Blending of multifiber yarn is, of course, best achieved by the widest possible dispersion of the different components of the blend. It is somewhat less obvious, but equally true, that the best obtainable blend will not be perfectly dispersed but randomly dispersed. To achieve a high degree of blending efficiency when the fibers are drawn on a draw frame, it might be supposed that the greater the initial distribution of the fibers to be blended, the better will be the end result of the blending process. This is because blending by drawing is a surface phenomenon and a higher ratio of available fiber blending surfaces to volume for dissimilar blend components exists when there are finer basic subdivisions of the different fibers. But blending in drawing takes place only by vertical migration of fibers because blending is a one-, not two-dimensional phenomenon. Consequently, superior blending efficiency results only when the slivers of fiber are so disposed relative to each other that the available blending surface to volume ratio is highest in the plane determined by the nips of the back rolls of the drafting system.

In accordance with the present invention, separate groups of slivers of fibers are fed to a guide mechanism, located immediately adjacent and in front of the back rolls of the drafting head of a conventional draw frame, which flattens and sandwiches the slivers into a web of blend components having a high surface to volume ratio in the drafting zone of the back rolls.

More particularly, in accordance with the present invention, separate groups of slivers of fiber are supported in their passage from the cans to the drafting system by a conventional creel and guides which keep the slivers separate from one another. After passing these guides, the slivers are fed into a second set of guides which produce a sandwich-type, three-layer web of the blend components by flattening the slivers into a sheet or ribbon and then superimposing alternate layers of the ribbons into a combined web. Thereafter, the combined web passes into the nips of the back rolls and through the drafting head and is discharged as a thin blended sheet or web.

For a better understanding of the present invention,

2

reference may be had to the accompanying drawings in which:

FIG. 1 is a schematic illustration of a lap machine in accordance with the present invention;

FIG. 2 is a perspective view of a guide mechanism in accordance with the present invention which feeds slivers of fiber to the back rolls of a drafting head;

FIG. 3 is a perspective view of the guide mechanism of FIG. 2 showing the feeding of slivers of fiber;

FIG. 4 is a sectional view taken along line 4—4 of FIG. 3; and

FIG. 5 is a sectional view showing the sliver configuration in the plane determined by the nips of the back rolls taken along line 5—5 of FIG. 4.

By way of example and for purposes of illustration, the present invention will be described below in the preparation of a 2 to 1 Dacron-cotton blend utilizing a lap machine having three drafting heads, although it will be understood that the invention is not limited to the illustrated example but comprehends the use of other blend components and blend ratios and the use of any number of drafting heads.

The invention may, for example, employ other natural fibers, such as wool, silk or the like and other synthetic fibers, such as rayon, nylon, acetate, polypropylene and the like.

The blended lap may be formed from different natural fibers, different synthetic fibers or, as in the illustrated example, some slivers may be formed of natural fibers while others are formed of synthetic fibers.

It will be understood, however, that the number, type and weight of the individual slivers fed to the drafting heads may be varied according to any particular blend desired in the resulting lap.

As shown in FIGS. 1 and 3, a plurality of Dacron slivers 2 and cotton slivers 4 are conducted from an appropriate number of cans 6 to the back rolls 8 of the drafting heads 10, 12 and 14 by means of a conventional creel (not shown) and two sets of guides 16 and 18, respectively.

The first set of guides 16 (FIG. 3) prevent any sliver intimacy from occurring before sandwiching in the guides 18 which could cause loss of sliver control in the back rolls 8, and are of conventional design. A second set of guides 18, located immediately adjacent and in front of the back rolls, in accordance with the present invention, comprise a plurality of lateral guide plates or dividers 20 and vertical guide plates or dividers 22 defining a plurality of three-tiered passageways 24 which taper convergently in the direction of the back rolls 8.

After passing over the guide 16, the Dacron slivers 2 are fed to the outside rows of the three-tiered passageways 24 of the guides 18 while the cotton slivers 4 are simultaneously fed to the middle row of passageways.

As shown in FIG. 4, the guides 18 flatten the slivers into ribbons and sandwich a flattened cotton sliver 4 between two flattened slivers of Dacron 2 producing a three-layer, sandwich-type web 26 having in the drafting zone of the back rolls 8 the configuration 28 shown in FIG. 5. Inasmuch as blending is a one-dimensional phenomenon and the guide 18 assures maximum surface contact to facilitate such blending, as described above, the guide assures a more uniform and complete blending of the yarns during processing in the drafting heads and subsequent operations in combing laps, or the like. The blending of the sliver configuration 28 depends strongly upon the good register between the three-layers of ribbons of the sandwich web 26.

The drafting heads 10—14 each produce a ribbon or sheet 30 of desired material which is directed to a table 32, where, in successive fashion, the ribbon nearest the delivery end is superimposed over the ribbon produced

by the adjacent head. The combined sheet 34 then passes through a calendar roll 36 and is wound into a lap 38. On reaching the required size, the lap 38 is conveniently rejected and is ready for further processing.

It will be understood by those skilled in the art that the above-described invention is susceptible of modification and variation without departing from its spirit and scope. Therefore, the invention is not deemed to be limited except as defined in the appended claims.

We claim:

1. In apparatus for blending fibers in which said fibers are provided by a plurality of slivers of which ones are respectively formed of differing ones of said fibers, and in which said slivers are fed to the back rolls of a drafting head, the improvement comprising an array of first guide plates disposed ahead of said rolls and spaced from each other in the axial direction of said rolls, an array of second guide plates extending in said axial direction between said first plates and coupled thereto to form therewith a guide structure, said second plates being spaced in a plane normal to said axial direction to form therebetween for said plurality of slivers a respectively corresponding plurality of passageways extending towards said rolls through said structure such that each two adjacent passageways are commonly bounded by one of said second plates, and said second plates being in respective planes which are parallel to the axes of said rolls and which converge in the direction towards said rolls to render said passageways convergently tapered in such direction so as to enable each of said passageways to flatten the sliver passing therethrough.

2. In a method for blending fibers by feeding to the back rolls of a drafting head and drawing through said head a plurality of slivers of which ones are respectively formed of differing ones of said fibers, the improvement comprising, drawing said plurality of slivers through a respectively corresponding plurality of passageways disposed ahead of said rolls and spaced from each other in a

plane normal to the axial direction of said rolls, each of said passageways being tapered in said plane convergently in the direction towards said rolls to terminate at an outlet of smaller dimension in said plane than the diameter of the entering sliver so as to impart a flattening in said plane to the sliver emerging from that outlet and a broadening of such sliver normal to such plane, and guiding such flattened slivers before entry thereof into the nip of said rolls so as to render the center lines of all said slivers in said plane and to produce a registering face to face relation between the broadened surfaces of such slivers.

3. The improvement in method according to claim 2 comprising the further step of bringing said emerging flattened slivers into engagement with each other at a location ahead of said rolls to thereby form of said slivers prior to entry thereof into the nip of said rolls a multilayer web wherein said slivers are parallel and the broadened surfaces thereof are in superimposed contacting relation.
